Application July 14, 1951, Serial No. 236,754

5 Claims. (Cl. 101—401.5)

1

This invention relates to type forming machines, and more particularly to machines for producing type pieces by the well known kneading process.

The forming of individual pieces of type material into appropriate pieces of type by this process is accomplished by a combined rocking and pressing action between a die matrix and a type blank or slug of suitable material. In actual practice, either the die matrix or the type slug may be the rocked member, and either the die may be pressed against the type slug or the type slug against the die. The uniformity and accuracy of the type pieces produced are dependent upon the maintenance of the same relationship between the type slug and the die matrix for each piece of type formed.

A preferred embodiment of the instant type forming machine may comprise a table on which is mounted a turret device. The turret contains six work holding fixtures spaced 60 degrees apart in its top surface. During the initial portion of each machine cycle, the turret is automatically advanced or indexed 60 degrees and is then locked in position by mechanism synchronized with the turret advancing mechanism. In this manner each work fixture is indexed in steps in a path around the table. As a work fixture is positioned in any one of two positions towards the front of the table, it is adapted to receive a type slug of suitable material. By successive indexings, each type slug is carried to a kneading position wherein a continuously rocking die matrix is automatically pressed against the type slug to form a piece of type. The next indexing of the turret carries the newly formed type piece to a position where it is partially ejected from the related work fixture. On the following indexing of the turret, the partially ejected type piece is moved into engagement with an ejector tool which completely removes it from its related work fixture. The next indexing of the turret carries the empty work fixture to a position where it may again be loaded with a type blank.

An object of this invention is to provide an improved mechanism for effecting a kneading action on a type slug wherein type pieces are produced accurately and efficiently.

Another object of this invention is to provide a type kneading machine which is light in construction and fast in operation.

2

Another object of this invention is to provide a type kneading machine which requires comparatively light pressure between the die matrix and the type slug during the type forming operation.

Another object of this invention is to provide a type kneading machine having novel means for adjusting and maintaining the position of the die matrix relative to the type slug.

10 Another object of this invention is to provide a type kneading machine having a turret mechanism with a plurality of novel work holding fixtures.

Another object of this invention is to provide a 15 type kneading machine having novel means for ejecting the completed type pieces from the machine.

Another object of this invention is to provide a 20 type kneading machine having novel mechanism for indexing a turret mechanism during a fixed portion of each cycle of the machine and novel mechanism linked to and synchronized with the indexing mechanism for locking the turret in position during the remaining part of each machine cycle.

25 Other objects of the invention will be pointed out in the following description and claims and illustrated in the accompanying drawings, which discloses, by way of example, the principle of operation and the best mode, which has been contemplated of applying that principle.

In the drawings:

Fig. 1 is a side elevation of the improved type kneading machine.

30 Fig. 2 is a front elevation of the improved type forming machine.

Fig. 3 is an enlarged horizontal sectional view taken on the plane of the line 3—3 in Fig. 2.

35 Fig. 4 is a partial vertical section taken through the turret, work table, and kneading head on the line 4—4 of Fig. 3 and shows a work fixture in the kneading position.

40 Fig. 5 is an enlarged vertical section taken on the line 5—5 of Fig. 3 and shows the mechanism for partially ejecting each type piece from its related work fixture of the turret.

Fig. 6 is a partial vertical section taken through the turret and table on the line 6—6 of Fig. 3 and shows the ejection mechanism for fully ejecting each type piece from its related work fixture.

45 Fig. 7 is a perspective view of the ejector tool.

Referring to Figs. 1 and 2, it will be noted that the type forming machine comprises a main frame, generally designated 9, which is secured to and supported by a base 10. The frame 9 comprises side members 11 and 12 which are separated by back members 13 and 14 and a front member 15, the members 13, 14, and 15 being integral with the side members. Secured to the top of the side members by screws 16 is a top plate 17. Each of the side members includes a horizontal shelf portion 19, and attached to these shelf portions and to the front member 15 is a work table 21. A rod 22 secured between an extension 23 of each side member and the front of its shelf portion 19 imparts added strength and rigidity to the shelf portions of the side members and to the front member 15.

Each of the side members 11 and 12 carry suitable bearing inserts to rotatably support the main power shaft 27 of the type forming machine. Secured to the shaft are three cams 28, 29, and 30 which effect the various automatic operations of the type forming machine as will be later evident. For driving the shaft, there is provided an electric motor 32 which is secured to the back frame member 13. A pulley 33 on the shaft of the motor operates through belts 34 to drive a combined pulley and flywheel 35 secured to one end of the shaft 27. The shaft 27 is continually rotated clockwise in Fig. 1 when the motor is energized and, on each revolution of the shaft, the machine goes through one complete cycle of operation.

Rotatably mounted on the work table 21 is a so-called indexing turret 37. Spaced 60 degrees apart in the top surface of the turret, as shown in Fig. 3, are six work holding fixtures generally designated 38. During the first part of each machine cycle, the turret is rotated clockwise 60 degrees to advance each work fixture one position. During the remainder of the cycle, the turret is positively locked in position. As the turret advances or indexes each work fixture to the front of the table or to the next index position clockwise from the front of the table, the machine operator inserts a type blank into the fixture. These two index positions are known as the "loading positions" of the turret.

By successive indexings of the turret, each type blank is advanced from the most clockwise loading position in Fig. 3 to an intermediate position, and thence to a position directly under a so-called kneading head 39. By a combined pressure and rolling action of the kneading head, an associated die matrix 40 (Fig. 4) automatically forms the type blank into a piece of type. After the type forming operation, the newly formed piece of type is advanced to a position where it is partially ejected from its work fixture. This position has been designated 41 in Fig. 3. The next indexing of the turret carries the piece of type to an ejector mechanism, generally designated 42, which lifts it from the related fixture and discharges it down a chute 43 into a suitable container. In other words, the operator attending the machine merely loads the type blanks into the empty work fixtures of the turret as they are indexed past him, the actual type forming operation, and the removal of the type pieces being automatic.

Referring to Fig. 4, it will be noted that the turret comprises a circular member 47 which rests on the table 21 and engages the outer race of a roller bearing 48. The bearing also rests on the table 21 with its inner race engaging the shoulder

49 of a stud 50 projecting into a mounting hole in the table and secured thereto, by screws 52. Mounted on the top of the circular member 47 is a circular member 53 having six openings 54 in which the work fixtures 38 are positioned. Adjacent to each of the openings and communicating therewith is a semicircular opening 55 having a slightly inclined inner wall 56, as shown in Fig. 4. A wedge member 57, mounted in each of the openings 55 and positively secured to the circular member 47 by a related screw 58, maintains a die block 60 of each fixture tightly against the accurately machined outerwall of the opening 54. As a result, each block is accurately positioned the same distance from the mounting stud 50. Four screws 61 secure each block to the circular member 47. The screws 58 and wedge members 57 also serve to rigidly secure the circular member 53 to the circular member 47. A screw 62 and washer 63 aid in maintaining the entire assembly on the stud.

Each of the work fixtures 38 comprises the die block 60 which has an opening 65 therein in which a blade 66 is slidably mounted. It will be noted in Fig. 4 that the portion of the opening 65 approaching the top surface of the block is of increasing width and, as a result, there is a wedge shaped clearance 67 between each side of the blade and the block at this point. The blade 66 extends through the block and into an adjacent opening 68 in the bottom circular member 47. Slidably mounted in the opening 68 is a plug 69 whose top surface is engaged by the bottom of the blade while its bottom surface rests in a groove 70 which is cut in a circular path in the table 21 as indicated in Fig. 3. The groove is cut in the table to varying depths so that, as the turret indexes each fixture, the bottom of the groove acts as a cam surface against the related plug 69. As a result, the blade 66 is lowered or raised in the opening 65 in the corresponding die block 60 dependent upon the actual position of the fixture relative to the table.

The groove 70 is cut to a depth as indicated at the left of Fig. 4 on that angular portion of the groove towards the front of the table. Consequently, as the turret indexes each work fixture in turn to the loading positions, the related blade 66 extends above its associated die block and is adapted to receive a type blank 71, as indicated. It will be noted that the type blank is supported entirely on the blade 66 and does not engage the die block 60.

As each work fixture is indexed from the most clockwise loading position in Fig. 3 towards the position directly under the kneading head, the groove 70 increases from the depth indicated at the left in Fig. 4 to the depth indicated at the right in Fig. 4. Consequently, if the related blade 66 has not, by its own weight, dropped to a lower position as indicated, the die matrix 40 of the kneading head, as it "kneads" the type blank into a piece of type, depresses the blade into this lowered position.

A type piece 72 of the form shown under the kneading head in Fig. 4 results from the actual type forming operation. During this operation, part of the metal of the original type blank 71 flows over the top of the die block 60 creating what is commonly referred to as "flash" 73. This "flash" or excessive metal is sheared from the type piece in a well known manner after the type piece is removed from the work fixture. It will also be noted that part of the metal of the original type blank is forced into the previously

mentioned wedge shaped clearance 67 and back side of the blade thus forming wedge shaped extensions 74 on the type piece. It will also be noted in Fig. 4 that the portion of the table 21 directly under the kneading head contains a hardened steel insert 75 adapted to support that portion of the turret and fixture under the kneading head.

After the type kneading operation, the next indexing of the turret positions the plug 69 of the fixture containing the newly formed type piece directly over the end of a lever 76, as indicated in Fig. 5. The lever extends under the turret in a slot 77 cut in the work table 21 and is pivotally mounted on a stud 78 carried by the table. A spring 79 extending between a recess in one end of the lever and a recess in the table 21 normally maintains the lever in a position free from the plug 69. Positioned directly above the outer end of the lever 76 is a plunger 80 which is slidably mounted in a member 81. The top of the plunger comprises an enlarged cylindrical portion 82, the member 81 being cut away, as indicated, in order to accommodate this enlarged portion and other related mechanism. The cylindrical portion of the plunger has two circular recesses 83 therein, each of which is adapted to receive a spring 84. The tops of the springs abut a plunger block 85 which is secured to the member 81.

During the portion of each cycle when the turret is locked in position, the member 81 is moved downward and then upward by mechanism to be later explained. Upon the downward stroke of the member, the plunger block 85 acts through the springs 84 to press the plunger 80 downward and effect a clockwise rotation of the lever 76. As the lever rotates, the plug 69 and the associated blade 66 of the related fixture are forced upward into the position shown in Fig. 5. Upward movement of the blade breaks any "seal" between the piece of type 72 and the related die block 60, and the type piece is partially ejected from the block, as indicated. Fixed to the blade is a pin 64 engageable with the block 60 for limiting upward travel of the blade. After partial ejection of the type piece, the plunger 80 restores upward in Fig. 4, and the spring 79 restores the lever 76 so that it is in position to repeat the above described operation during the next machine cycle.

It will be noted in Fig. 6 that the portion of the groove 70, extending clockwise in Fig. 3 from the so-called partial eject position 41 to the eject mechanism 42, is of steadily decreasing depth. Consequently, if the plug 69, blade 66, and type piece 72 follow the lever 76 as it restores, the inclined surface of the groove over which the plug rides during the next indexing of the turret will lift the plug, blade, and type piece upward again. This inclined portion of the groove insures that each type piece will occupy the same partial eject position as it approaches the eject mechanism.

Referring to Figs. 6 and 7, the eject mechanism 42 comprises a lifter tool 87 which is rigidly secured to one end of a lever 88. The other end of the lever is pivotally mounted on a shaft 89 carried by a block 90 which is secured to the work table 21. The lifter tool 87 contains a recess 91, and projecting into the recess from the lower ends of its side walls are two blade-like flanges 92. The flanges terminate short of engagement with each other so that a slot 93 is formed between their ends, as indicated in Fig. 7. A member 94 extends into a slot 95 in the lifter

tool and is pivotally connected to the lifter by a stud 96. Secured to the lower end of the member 94 is a so-called pusher 99 having a recessed end 100 which extends into the recess 91. The top end of the member 94 is connected through a link 101 to a cam follower 102 which is pivotally mounted on the lower end of a support 103 secured to the underside of the top plate 17. The follower 102 carries a roller 104 for cooperation with the previously mentioned cam 30 on the power shaft 27. The cam is so shaped that during the indexing movement of the turret, the lifter tool 87 almost engages the top of the turret, as indicated in Fig. 6. When the lifter is in this position, the related slot 93 is directly in the circular movement path of the partially ejected type piece. Consequently, during the final part of the indexing movement of the turret, the partially ejected type piece moves into the recess 91 of the lifter as indicated in Figs. 6 and 7 with the wedge shaped extensions 74 of the type piece moving into the slot 93. When the indexing movement of the carriage ceases, the forward edge of the type piece is adjacent to the pusher 99 while the flash portions 73 of the type piece rests on the top of the flanges 92.

During the following machine interval when the turret is stationary, the cam 30 rocks the follower 102 counterclockwise in Fig. 1. The resultant upward movement of the connecting link 101 and associated member 94 rotates the lifter tool 87 and lever 88 clockwise in Fig. 6 around the shaft 89 and into the upper dotted line position. This motion of the lifter removes the type piece from its related work fixture. It will be noted that as the lifter moves into this latter position, it is also displaced clockwise relative to the member 94. As a result, the edge of the pusher 99 engages the type piece and slides it out of the recess 91 during the latter part of the clockwise movement of the lifter. When the lifter reaches the dotted line position indicated, the type piece drops from the flanges 92 and into the chute 43. The outer end of the flanges 92 of the lifter tool almost engage an arcuate extension 105 of the chute 43 during most of the clockwise movement so as to prevent premature discharge of the type piece. The chute discharges the ejected type piece into a suitable bin secured underneath the work table 21. Thereafter, the cam 30 restores the mechanism to the lower position indicated in Fig. 6 in preparation for the next eject operation.

The mechanism provided for indexing the turret 37 60 degrees clockwise during the initial portion of each cycle, and for locking the turret in position for the remainder of the cycle, and for unlocking the turret at the end of the cycle in preparation for the next indexing operation, is controlled by the previously mentioned cam 28 secured to the shaft 27.

Rotatably mounted at the mid point of a follower arm 106 (Fig. 1) is a roller 107 which operates with the cam 28. One end of the arm 106 is pivotally mounted on the side frame 11 by a suitable fastening 108. The arm 106 is continually biased counterclockwise in Fig. 1 by means of a member 109 to yieldingly maintain the roller in contact with the cam.

The member 109 comprises an enlarged shoulder portion 110 and a rod portion 111. The shoulder portion 110 is pivotally secured to the arm 106 while the rod portion 111 is adapted to slidably engage an opening in an extension 114 of the side frame 11. Slidably mounted on the

rod portion of member 109 is a ball member 115. A spring 116 surrounds the rod portion 111 between the shoulder portion 110 and the ball member. One end of the spring maintains the ball member against a recess 117 on the extension 114 while the other end of the spring 116 acts on the shoulder 110 and yieldingly biases the arm 106 counterclockwise.

Pivotedly connected to the outer end of the arm 106 is a link 119 which is pivotedly connected to one end of a short arm 121 of a bellcrank 122. The bellcrank comprises two distinct parts, the short arm 121 which is secured to a shaft 123, and a long arm 124 loosely mounted on the shaft 123 adjacent to the short arm. The shaft 123 is rotatably supported by a bearing 125 carried by a member 126 which is secured to supports 127 attached to the work table 21.

The short arm contains four spaced recesses 128 (Fig. 3) at one side adapted to receive four tapered pins 129 extending from one side of the long arm. Adjacent the other side of the long arm is a clamp 130 which is slidably mounted on the shaft 123 and on two bolts 131 carried by the short arm. A spring 132 mounted on each of the bolts, urges the clamp 130 towards the short arm so that the pins 129 of the intervening long arm are normally maintained engaged with the mating recesses 128 of the short arm. By this construction, the two arms are yieldingly "locked" together so that they normally rock as a unit, with the shaft 123, in response to an up and down movement of the link 119.

Pivotedly connected to the lower end of the long arm 124 is a link 135 which is connected to the bifurcated end of a square rod 136 resting on the table 21 and adapted for reciprocation in a path across the front of the table. Blocks 137, 138, and a plate 139 secured to the table, guide the rod in a fixed path. Secured to the rod 136 is a block 140 having one end of a link 142 pivotedly mounted therein. Mounted on the other end of the link is a pawl 143 and a spring 144 connected between an extending portion 145 of the pawl, and the link 142, urges the pawl counterclockwise in Fig. 3 towards the bottom circular member 47 of the turret. The circular member contains recesses 146 spaced 60 degrees apart around its circumferential surface, each recess being aligned radially with one of the work holding fixtures 38 and adapted to receive the nose 147 of the pawl. Fig. 3 shows the position of the turret, pawl 143, and related mechanism immediately prior to an indexing operation.

As the square rod 136 and associated block 140 shift to the left in Fig. 3 in response to the clockwise rocking of the bellcrank 122 in Fig. 2, the resultant movement of the pawl 143 rotates the turret clockwise. As the turret rotates or indexes clockwise, the pawl is displaced relative to the link 142, while the link 142 is displaced relative to the block 140. However, at all times during the actual indexing operation, the tail of the pawl rides on the circumferential surface of the turret so that the pawl occupies the same angular position relative to the turret as shown in Fig. 3. By this construction, the straight line movement of the square rod 136 is translated into an angular movement of the indexing pawl. When the square rod 136 reaches its extreme left hand position in Fig. 3, the pawl 143 occupies the dotted line position indicated, the pawl having advanced the turret 60 degrees clockwise during the movement of the rod. The turret is then

locked in position for the remainder of the cycle by mechanism to be later explained.

During the machine interval when the turret is locked in its new position, the square rod restores to the right towards the position shown in Fig. 3. At the beginning of the restoring movement of the rod, the inclined surface 149 at the nose of the pawl is forced against the side of the recess 146 in which it is positioned. As a result, the pawl is cammed clockwise relative to the link 142 until its nose is disengaged from the recess. Thereafter, the nose of the pawl rides on the circumferential surface of the circular member 47 of the turret until it drops into the next recess 146. The mechanism is then in condition for the next indexing operation.

If for any reason the normal indexing movement of the turret or the movement of the related indexing mechanism is interfered with, the normal movement of the long arm 124 of the bellcrank 122 is also affected. With the long arm 124 blocked against movement, the continued movement of the short arm 121 effects a camming pressure between the pins 129 of the long arm and the mating recesses 128 of the short arm. This camming pressure is greater than the pressure exerted by the springs 132 and, as a result, the pins 129 are disengaged from the recesses 128. Consequently, the short arm of the bellcrank is able to complete its cycle of operation independent and disconnected from the long arm. In this manner, damage to the mechanism is prevented.

The mechanism provided for locking the turret in position during the type kneading operation, which takes place during the latter part of each cycle, is most clearly shown in Figs. 1 and 3. It will be remembered that the short arm 121 of the bellcrank 122 is directly fixed to the shaft 123 and effects a rocking action of the shaft as the link 119 moves up and down. Secured to the other end of the shaft 123 is an arm 152 carrying a stud 153 which supports a roller 154. The roller 154 coacts with one arm 155 of a bellcrank 156 which is pivotedly mounted on a stud 157 carried by the support 127. The other arm 159 of the bellcrank 156 engages a block 160 secured to a push rod 161, the rod being slidably supported in blocks 162 and 163 which are secured to the work table 21. The end of the push rod 161 in turn coacts with an arm 165 of a bellcrank 166 which is pivotedly mounted on a stud 167 secured to the work table 21. A spring 168 surrounds the rod 161 and acts between the guide block 163 and a block 169 secured to the rod for urging the latter toward the left in Fig. 3. The other arm 171 of the bellcrank 166 engages a slot in a pin 173 which is slidably mounted in a guide block 174 secured to the work table 21. A spring 175 connected between the arm 165 and the work table 21 continually biases the bellcrank 166 clockwise in Fig. 3 so that the associated pin 173 is urged towards the turret 37. The end of the pin is adapted to engage an aligned recess 146 on the turret during the latter part of each cycle in order to lock the turret in position.

Fig. 3 shows the position of the turret locking mechanism immediately before an indexing operation of the turret. It will be noted that the end of the locking pin 173 is disengaged from the adjacent recess 146 of the turret.

During the latter part of each machine cycle, the bellcrank 166 is moved clockwise in Fig. 3 so that the nose of the pin 173 engages the ad-

jacent recess 146 in the turret to lock it in position. The type kneading operation then takes place, and the shaft 123 is rocked to restore the pawl 143 towards the position indicated in Fig. 3 in preparation for the next indexing movement of the turret. During the latter part of the clockwise rocking of the shaft 123, the roller 154 carried by the arm 152 engages the arm 155 of the bellcrank 156 and rocks the bellcrank on its mounting stud 157. The resulting movement of the arm 159 of the bellcrank against the block 160 pushes the rod 161 for rocking the bellcrank 166 in a direction to disengage the pin 173 from the recess 146.

With the mechanism in the position indicated in Fig. 3, the following sequence of operations takes place: As the shaft 123 starts to rotate clockwise in Fig. 2 in response to the downward movement of link 119, the pawl 143 starts to index the turret clockwise in Fig. 3 in the manner previously explained. As the shaft rotates clockwise, the resultant movement of the arm 152 and associated roller 154 permits the spring 168 to start to restore the rod 161 towards the left in Fig. 3. The bellcrank 166, by reason of spring 175, tries to follow the rod 161 and move the associated pin 173 towards the turret 37. By this time, however, the pawl 143 has advanced the turret a sufficient amount so that the end of the pin 173 engages the circumferential surface of the turret. As the shaft continues to rotate, the rod 161 restores further to the left in Fig. 3. However, since the end of the pin 173 is now riding on the circumferential surface of the rotating turret, further clockwise movement of the bellcrank 166 is prevented and a clearance develops between the end of the rod and the arm 165 of the bellcrank 166. When the next recess 146 in the turret comes adjacent to the end of the pin 173, the spring 175 is able to rotate the bellcrank 166 clockwise in Fig. 3 to engage the pin in the recess. The bellcrank comes to rest with its arm 165 engaging the end of the rod 161. Clockwise movement of the shaft 123 ceases at this time with a new work fixture 38 being positioned directly towards the front of the work table. Thereafter, the upward movement of the link 119 rotates the shaft 123 clockwise, and the sequence of operation as described above is repeated.

Adapted for vertical reciprocation relative to the turret and the work table is a ram generally designated 176 in Figs. 1 and 2. This ram includes rail portions 177 at each side slidably engaging mating grooves cut in the inner edges of the side frames 11 and 12. Secured to the top of the ram are two bolts 178 which extend through openings in the top plate 16 of the frame structure and through the centers of related coil springs 179. Attached to the top of each of the bolts is a plate 180 which abuts the top of the related spring 179, the bottom of the spring resting on a shoulder on the top plate 16. The springs 179 continually bias the ram upwards to maintain a roller 182 mounted on a shaft 183 carried by the ram, in continual engagement with the cam 29 on the main power shaft 21. The cam 29, which is shaped as shown in Fig. 1, is adapted to move the ram downwards toward the turret during the latter part of each cycle when the turret is locked in position. Figs. 1 and 2 show the ram shortly after it has started to move upwardly from its extreme lower position.

The mid portion of the shaft 183 on which the roller 182 is mounted is eccentric from the end

portions of the shaft which are supported by the ram. Secured to one end of the shaft is a crank 184. The other end of the shaft engages an opening in a plate 185 which is secured to the ram. 5 A slot extends from this opening in the plate to one outer edge of the plate. A screw 186 carried by the plate normally squeezes the portion of the plate on each side of the slot towards each other so that the shaft 183 is locked to the plate 10 and, therefore, to the ram. When desired, however, the shaft may be "unlocked" and then adjusted angularly relative to the ram by the crank 184. In this manner, the mid portion of the shaft supporting the roller may be shifted relative to the ram. As a result, the length of the stroke of the ram may be varied as desired.

Secured to the lower end of the ram is a plate 187 which rigidly supports two shafts 188 and 189. The plate 187 is recessed around a portion 20 of the shaft 188 to permit a link 191, which has a suitable bearing insert, to pivotally engage the shaft. In a similar fashion, the plate is recessed around a portion of the shaft 189 to permit a link 192 to pivotally engage the shaft. Pivotally supported by suitable bearing inserts 193 and 194 in the other ends of the links 191 and 192 respectively, is the previously mentioned kneading head 39 which is built so as to eliminate all unnecessary weight. Adjustably locked to the 25 kneading head, in a manner later to be explained, is the die matrix 40 having an engraved version of the desired type character in its lower surface. Secured to each end of the kneading head is an arm 195, the lower end of each of the arms 30 having a shaft portion 196 (Fig. 3) integral therewith. Each of the shafts 196 engage a roller bearing 197 carried by a related guide member 198. The roller bearings serve to pivotally maintain the kneading head and associated die matrix 35 directly over each type blank as it is indexed into the kneading position. It will be noted that the end of one shaft 196 slidably engages a block 199 secured to the table while the end of the other shaft 196 slidably engages the previously 40 mentioned block 90 secured to the table. These blocks 199 and 90 accurately position the kneading head so that it can not shift laterally relative to the turret. The rearward end of each guide member 198 carries a suitable bearing insert 45 which pivotally engages a projecting end of a shaft 200. The shaft includes eccentric portions 201 which engage support members 202 secured to the work table. A screw 203 carried by each support member is normally tightened against the shaft to lock it to the support members. The 50 portion of the shaft between the supports 202 is rectangular in cross section so that the shaft 200 may be adjusted angularly relative to its supports with a hand wrench upon release of the lock screws 203. As the shaft is shifted angularly, the eccentric portions 201 shift the shaft 200 and in turn the guide members 198 forward or rearward relative to the turret as desired. In 55 this manner, very accurate control of the roller bearing pivot points of the kneading head is obtained.

The kneading head includes an upwardly extending portion 205 which projects into a slot 206 in the plate 187. A wrist pin 207 is secured 60 to the upper end of the extending portion 205, the projecting ends of the pin engaging bearings carried in the bifurcated end of a connecting rod 208. The other end of the connecting rod (Fig. 1) carries a bearing insert which rotatably 65 engages a crankshaft 210. The crankshaft is

11

rotatably supported by bearings mounted in the rearward portion of the plate 181. Mounted on each end of the crankshaft is a flywheel 211. One of the flywheels is provided with a groove to receive a belt 212 which engages a pulley 213 of a drive motor 214 secured to the back member 15 of the frame structure. The motor 214 is continually energized when the type forming machine is in operation, and the resultant rotation of the crankshaft 210, through the connecting rod 208, imparts a rapid back and forth movement to the top of the kneading head 39. Since the bottom of the kneading head is pivotally constrained by the roller bearings 197 of the guide members 198, an oscillatory rolling motion results at the surface of the die matrix 40.

The downward movement of the ram 176 each cycle presses the die matrix against a type blank, which is then positioned directly under the die matrix. This pressing action combined with the rolling motion of the die matrix, effects a kneading action on the type blank. As a result, the exact complement of the engraving in the die is formed on the type blank. During the type forming operation, part of the metal of the original type blank flows into the clearances 67 in the fixture, as previously explained, thus forming wedge shaped extensions 74 in the type piece. These wedge shaped extensions are utilized in later mounting the type piece on a type bar in a well known manner. The plate 81, on which the mechanism for operating the lever 76 is mounted, is secured to the bottom of the plate 181. Consequently, as the ram moves downward during each type forming operation, the lever 76 is simultaneously operated to partially eject the previously formed type piece from its related work fixture 38.

The die matrix is adjustably mounted in the kneading head in a manner most clearly shown in Fig. 4. A recess 216 is formed in the kneading head so that it opens at its upper end into a transverse bore 217 formed through the head at an incline as shown. The die matrix 40 fits within the recess and is held in place by a member 218 clamped to the kneading head by bolts 219. A bolt 220 extends through the bore 217 and is shaped to provide a flat surface 221 which is engageable with the end of the die. By manipulating nuts 222 on the bolt 220, the latter may be shifted longitudinally through the bore 217. As a result, the surface 221 changes its vertical position and determines the amount which the die matrix extends below the bottom of the kneading head. In this manner, the engraved portion of the die matrix may be accurately maintained on alignment with the center of the pivot shafts 196 of the kneading head. Both ends of the die matrix may have the desired character engraved therein so that when one end of the die becomes worn, it may be turned around to position the unworn end in the type forming position.

It will be appreciated that as a result of the manner of mounting the kneading head, it is at all times accurately maintained in its operational path with a minimum of play. Consequently, the associated die matrix is able to apply the same uniform kneading motion to each successive type blank resulting in the production of uniform and accurate type pieces. The manner of mounting the kneading head and imparting the kneading action to the head, combined with the light mass of the head, enables the machine to form type pieces rapidly.

12

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

We claim:

1. A cyclically operable type forming machine comprising, in combination, a stationary frame having a work table, a turret rotatably mounted on said table, a work member, a die matrix rigidly secured to said work member, elongated guide members for said work member, means pivotally connecting said work member to one end of said guide members, means for pivotally connecting the other end of said guide members to said stationary frame, said last mentioned means being adjustable for positioning said work member laterally over said turret, a plurality of spaced holding fixtures carried by said turret, each fixture being adapted to hold a work piece, means for rotating said turret a predetermined distance each cycle so as to position said fixtures successively under said die matrix, means for rocking said work member on said guide members, and means for moving said work member so as to engage said die matrix with a work piece while said work member is being rocked.

2. A type forming machine comprising, in combination, a stationary frame, means mounted on said stationary frame for supporting a type blank, a ram reciprocably guided on said stationary frame for movement vertically relative to said supporting means, means for reciprocating said ram, a work member carrying a die matrix at its lower end, a link pivotally connected at one end to said ram and pivotally connected at its other end to said work member at a point between the ends of the latter, an elongated member pivotally connected at one end to said stationary frame and pivotally connected at its other end to the lower end of said work member, said elongated member operating to hold said die matrix in position for engagement with said type blank as said work member is moved downwardly, and means connected to the upper end of said work member for rocking the latter about said elongated member so as to produce a kneading action on said type blank by said die matrix.

3. The type forming machine of claim 2 including guide blocks secured to said stationary frame and slidably engaging said work member on opposed sides of its lower end for preventing movement of the work member laterally in one direction relative to said supporting means.

4. The type forming machine of claim 2 further characterized in that the pivotal connection between the one end of the elongated members and the stationary frame may be shifted so as to permit a lateral adjustment of said work member relative to said supporting means in the direction of said rocking action.

5. A type forming machine comprising, in combination, a stationary frame, means mounted on said frame for accurately supporting a work piece in a type forming position, a member reciprocably guided on said frame for movement at right angles relative to said support means, means for reciprocating said member, a work member, a plurality of links each pivotally connected at one

13

end to said reciprocable member and at the other end to said work member at a point between the ends of the latter, said links serving to impart the motion of said reciprocable member to said work member, a plurality of elongated guide members each pivotally connected at one end to said frame and at the other end to an end of said work member adjacent the support means, said elongated guide members operating to guide said work member for engagement with said work piece as said work member moves toward said support means, and means connected to the other end of said work member for rocking the latter

5

14

about said elongated guide members so as to produce a kneading action on said work piece by said work member.
